[57] CLAIM

The ornamental design for a toothbrush sanitizing capsule, as shown and described.

DESCRIPTION

FIG. 1 is a front elevational view of a toothbrush sanitizing capsule showing our new design;

FIG. 2 is a rear elevational view thereof;

FIG. 3 is a side elevational view thereof, with the opposite side being a mirror image;

FIG. 4 is a top plan view thereof;

FIG. 5 is a bottom plan view thereof;

FIG. 6 a perspective view thereof, with the lid omitted for clarity of illustration only;

FIG. 7 is a top plan view thereof;

FIG. 8 is a side elevational view thereof.

FIG. 3

FIG. 2

FIG. 1

*FIG. 4**FIG. 5**FIG. 7**FIG. 6**FIG. 8*
